UNITED STATES PATENT OFFICE.

JOHN E. ARTHUR, OF LANE, AND ALBERT D. KARR, OF CLINTON, ILLINOIS.

LINK-BLOCK.

SPECIFICATION forming part of Letters Patent No. 727,732, dated May 12, 1903.

Application filed October 9, 1902. Serial No. 126,622. (No model.)

To all whom it may concern:

Be it known that we, JOHN E. ARTHUR, of Lane, and ALBERT D. KARR, of Clinton, in the county of DeWitt and State of Illinois, have 5 invented an Improved Link-Block, of which the following is a specification.

This invention is applicable to the link-motion of a locomotive, to rotary engines of the type described in Patent No. 699,740, 10 granted to John E. Arthur May 13, 1902, and to any machine in which a shaft rotates in a 15 slideable bearing.

The object of the invention is to take up 15 for wear in the shaft-boxing and the slide- 20 bearings at a single operation.

The invention is exemplified in the structure hereinafter described, and it is defined 25 in the appended claim.

In the drawings forming part of this specification, Figure 1 is a plan of one face of the link-block. Fig. 2 is an elevation of one edge of the block. Fig. 3 is a plan of the face of the block opposite that shown in Fig. 1. Fig. 4 is a section on line X in Fig. 3. Fig. 5 25 shows the internal configuration of one of the slide-boxes. Fig. 6 shows the internal configuration of one of the quarter-boxes. Fig. 7 is a detail of one of the wedges used to take up wear.

The device comprises a pair of quarter-boxes concaved to embrace a shaft and provided with flanges 2, a pair of slide-boxes 3, having flanges 4, and a pair of wedges 8, having threaded stems 9, by means of which they 30 are drawn lengthwise to spread the quarter-boxes and the slide-boxes apart. The slide-boxes have their internal surfaces inclined to form apexes 5 at the centers of the boxes, and the quarter-boxes are beveled on their 35 sides to conform to the inclines of the slide-boxes, as shown in Fig. 3. The slide-boxes 40

have inclined surfaces 6 in their ends, and wedges 8 fit against inclines 6 and against the quarter-boxes. Stems 9 of the wedges extend through flanges 2 of the quarter-boxes, 45 and nuts 10 on the threaded extensions of the stems provide means for drawing the wedges up to compensate for wear. Spaces 7 are cut away at the centers of the ends of the slide-boxes to receive the stems of the 50 wedges.

Whenever it is desired to force the quarter-boxes inward against the shaft and the slide-boxes outward against the link or other slide bearing, the nuts 10 are screwed onto 55 stems 9 and the wedges are drawn into the boxing. The wedges 8 force the quarter-boxes inward, and the wedge-shaped sides of the quarter-boxes act on the inclined surfaces of the slide-boxes to spread the slide- 60 boxes against the slide-bearings.

We claim—

A link-block consisting of a pair of slide-boxes the internal surfaces whereof incline inward toward the center of the boxes and 65 form inward-presented apexes, a pair of quarter-boxes fitting inside the slide-boxes and having their sides wedge-shaped to conform to the inclined internal surfaces of the slide-boxes, and a pair of wedges placed between 70 broad surfaces of the quarter-boxes and internal surfaces of conjoining ends of the slide-boxes, and means for moving the wedges to tighten the boxes, substantially as described.

In testimony whereof we sign our names in 75 the presence of two subscribing witnesses.

JOHN E. ARTHUR.
A. D. KARR.
